DISCHARGE LAMP STARTING CIRCUIT

George A. Freeman, East Orange, N. J., assignor
to Westinghouse Electric & Manufacturing
Company, East Pittsburgh, Pa., a corporation
of Pennsylvania

Application September 27, 1941, Serial No. 412,578

4 Claims. (Cl. 315—100)

The present invention relates to discharge lamps and more particularly to what are known to the art as fluorescent lamps.

It is a recognized phenomenon with lamps of this type that a higher voltage is required to start them than for continued operation. Various circuit arrangements are now being extensively employed which operate successfully for lower wattage lamps wherein the starting voltage required is not greatly in excess of line voltage. However, as the wattage of such lamps is increased, the starting and operating voltage likewise increases; and as the operating or lamp voltage approaches line voltage, the problem of starting and operating becomes more and more complex.

Although many different types of circuits have likewise been employed in connection with discharge lamps wherein the operating voltage very closely approaches line voltage, they have not been very satisfactory. This is primarily due to the application of the higher starting voltage to the thermionic electrodes of the lamp before they have been heated to maximum electron-emitting temperature, causing sputtering of the electrode coating, resulting in comparatively short lamp life.

It is accordingly an object of the present invention to provide a starting and operating circuit for a discharge lamp requiring a lamp voltage closely approaching line voltage.

Another object of the present invention is the provision of a starting and operating circuit for a discharge lamp requiring a lamp voltage approaching available line voltage and wherein the higher starting voltage is not applied to the lamp until the thermionic electrodes have been heated to maximum electron emissivity.

A further object of the present invention is the provision of a starting and operating circuit for a discharge lamp wherein the higher starting voltage is not applied to the thermionic electrodes of the lamp until they have been heated to maximum electron emissivity, thus prolonging the useful life of the lamp.

Still further objects of the present invention will become obvious to those skilled in the art by reference to the accompanying drawing, wherein the single figure is a diagrammatical illustration of the starting and operating circuit for a discharge lamp in accordance with the present invention.

Referring now to the drawing in detail, a discharge lamp 5 is shown provided with the customary thermionic electrodes 6 and 7 comprising filaments coated with a material which gives

off a copious flow of electrons when heated, such as an oxide of barium, strontium, or the like. The lamp envelope is provided with a gas, such as argon, neon, helium or the like, to facilitate starting, and a small quantity of a vaporizable metal, such as mercury. The interior of the envelope is also coated with a material which is excited by the invisible ultra-violet radiations to produce visible light.

10 As shown, the lamp is designed to operate from the customary domestic source of electrical energy of approximately 110 volts which supplies the energy for first heating the electrodes to an electron-emitting temperature and thereafter supplies the discharge current. Assuming, for example, the lamp is of about 40-watt consumption, the electrodes will have such a spacing that approximately 100 volts is required to sustain a discharge, which very closely approaches the line voltage of 110 volts. Moreover, a lamp of this wattage requires a starting voltage surge in excess of 220 volts once the electrodes are heated to maximum electron-emitting temperature.

15 For the purpose of heating the electrodes 6 and 7 to an electron-emitting temperature, one terminal of the electrode 6 is connected to one side of the domestic source of supply, and in a similar manner one terminal of the electrode 7 is connected through a reactor or choke coil 8,

20 capacitor 9, and switch 10, to the opposite side of the source of supply of 110 volts. To complete a series circuit to the electrodes, their remaining terminals are, preferably, connected together through an inductance 12 as shown in the drawing.

25 30 35 The circuit thus far described differs not at all from the prior art since it is substantially at resonance and includes elements previously employed. Although such circuit would operate to initiate a discharge between the electrodes 6 and 7 upon closure of the switch 10, there is nothing to prevent the high voltage developed across inductance 12 from starting the discharge before the electrodes have attained proper electron-emitting temperature which invariably causes

40 45 sputtering of the electrode coating with resulting short lamp life.

To prevent such undesired result in accordance with the present invention, the constants of the circuit are so designed that insufficient current initially flows through the reactor 8 and inductance 12 to heat the electrodes 6 and 7 up to a temperature where a discharge will occur prematurely.

The net reactance of capacitor 9 plus reactor 8 must be capacitive and of such value to fix the

arc current at its rated value which is 45 ampere for a 40-watt lamp. The net reactance of the capacitor 9 plus the reactor 8 and inductance 12 is reactive and of such value as to develop approximately 220 volts across the inductance 12 for operating a glow switch 13. This voltage across inductance 12 is insufficient to initiate a discharge between the electrodes 6 and 7, particularly as they are not heated due to the flow of insufficient current therethrough. The circuit also has a leading power factor of over 80%.

To complete a series heating circuit for the filamentary electrodes to assure their being heated to maximum electron-emitting temperature and at the same time initiate a discharge once they are heated, the glow relay tube 13 above mentioned is provided for short-circuiting the inductance 12. This glow relay tube 13 is of the type shown and described in Patent No. 2,200,443, issued May 14, 1940, to E. C. Dench, and assigned to the same assignee as the present invention, and it is believed that it need not be herein described in detail. It should suffice to say that upon the application of the voltage for which it is designed, which in the present instance is 220 volts, a glow discharge occurs which would not occur at the line voltage, since the glow relay tube is inoperative at 110 volts. This glow discharge heats the electrodes of the relay tube and since one is a bimetallic electrode, it deflects into engagement with the other electrode to short-circuit the discharge.

Inasmuch as the glow relay tube, as hereinbefore mentioned, is in parallel with the inductance 12 and upon closure of the switch 10 a voltage of approximately 220 volts is induced across the inductance 12, such voltage is sufficient to initiate the discharge in the glow relay tube 13. Also, upon engagement of the electrodes of the glow relay tube to short-circuit the discharge, the inductance 12 is likewise short-circuited and a series heating circuit completed for the filamentary electrodes of the lamp 5. While previously insufficient current flowed through these electrodes 6 and 7, due to the constants of the circuit, they now receive adequate heating current and are brought up to maximum electron heating temperature very rapidly, the time delay during which the electrodes of the glow relay tube remain in engagement with each other being sufficient for this purpose.

When the bimetallic electrode cools and separates from its cooperating electrode, a high voltage surge results from the series reactor 8 sufficiently above 220 volts to initiate a positive column discharge between the now preheated lamp electrodes 6 and 7. Once this latter discharge starts, the lamp voltage drops to approximately 100 volts which is insufficient to again start a discharge in the glow relay tube. Moreover, the filamentary electrodes 6 and 7 are then heated mainly by the discharge since circuit flow through the inductance 12 is reduced. If, however, the lamp 5 should for any reason fail to start on the first operation of the glow relay tube 13, the latter will again repeat its cycle of operation without deleterious effect upon the lamp electrodes until the lamp does start.

It should perhaps be pointed out that although a glow relay tube 13 will operate satisfactorily in the circuit arrangement such as shown in the above mentioned patent, this is because the lamp therein shown is of shorter length wherein the lamp voltage is approximately 60 to 70 volts, considerably below line voltage. However, with

longer lamps which have voltages approaching more closely the line voltage, a higher voltage glow relay tube is used so that the lamp voltage or line voltage, which are of the same order of magnitude, will not operate it.

For example, if the relay is designed for a line voltage of 110 volts, as in the above noted patent, it would continue to repeat its operation when employed with a higher voltage lamp which has a lamp voltage approximating that of line voltage and the lamp would not start. To avoid this by employing a relay tube designed for 220-volt operation on a 110-volt line and with a required lamp voltage of 100 volts, insufficient voltage would be available to cause operation of the relay in the absence of the inductance 12. Moreover, use of the inductance without the glow relay tube would mean a different relation of the circuit constants to permit sufficient current flow for heating the electrodes of the lamp and at the same time the circuit would be subject to the disadvantage avoided by the present invention, as before mentioned, of allowing application of a high starting voltage prior to the electrodes being heated to optimum electron-emitting temperature.

In the preferred form thus far described it will be obvious that there is a small flow of current through the electrodes prior to operation of the glow relay tube, which as before mentioned is insufficient to heat the lamp electrodes to any appreciable extent. By the same token, during operation of the lamp there will likewise be a flow of the same low current value through the lamp electrodes and through the inductance 12 since the latter completes a series heating circuit when not short-circuited by the glow relay tube.

Although it is believed preferable to allow this small flow of current through the electrodes, it may be avoided if desired by connecting the inductance in the circuit as shown at 14 by the dotted lines in the figure, in lieu of the parallel connection with the glow relay tube 13 on the opposite side of the lamp electrodes, as shown by the solid lines for the inductance 12. This arrangement still permits the voltage built up across the inductance 14 to be impressed across a glow relay 13 with resultant operation of the latter and at the same time prohibits any flow of heating current through the lamp electrodes prior to operation of the glow relay tube, as well as during operation of the lamp. The total efficiency of the circuit is accordingly enhanced somewhat since the current through the inductance 14 would not flow through the lamp electrodes where heat loss results therefrom.

It should perhaps be noted that while the preferred circuit arrangement as above described is designed primarily for the starting of a discharge lamp from a commercial source of supply of 110 volts and where the lamp voltage closely approaches line voltage, such arrangement also will operate efficiently when employed with a line voltage of 220 volts and where the lamp is designed for operation from such source of supply, but where the lamp voltage is below line voltage, obviously the constants of the circuit would be somewhat different with this line voltage of 220 volts. This particular circuit arrangement when employed with a line voltage of 220 volts compensates for line voltage fluctuations in holding the electrodes at optimum emitting temperature.

For example, assuming the line voltage is 220 volts instead of 110 and that the operating voltage of lamp 5 is substantially below this voltage, dur-

ing operation of the lamp as the line voltage decreases due to fluctuations, more current will flow through the inductance 12 and less current will flow through the lamp. The lower heating of the cathode from the arc is compensated by increased heating resulting from increased current flow through the inductance 12. Light output from the lamp is lowered considerably at the same time due to reduced arc current. A further advantage of this circuit when employed on a 220-volt line resides in the fact that it can be employed in applications where a variable light intensity is desired without deleterious effect on lamp life.

It thus becomes obvious to those skilled in the art that a circuit for a discharge lamp is herein provided in which the lamp is efficiently operable from the customary domestic source of potential despite the fact that its operating voltage very closely approaches line voltage. Furthermore, the constants of the circuit are so designed that relatively low current flows through the filamentary electrodes until the circuit is conditioned to enable them to be heated to optimum electron-emitting temperature prior to the application of the high starting voltage, thus preventing sputtering of the electron-emitting electrode coating and prolonging the useful life of the lamp. Moreover, by connecting the inductance on the opposite side of the lamp electrodes to the glow relay tube, flow of any current through the lamp electrodes prior to operation of the glow relay can be readily prevented. By employing the circuit arrangement of the present invention in connection with a 220-volt source and where the lamp voltage is materially lower than line voltage, a variable light source is obtained and wherein line voltage fluctuations are compensated for by automatically increasing the flow of current through the inductance as the line voltage decreases, thus preventing any deleterious effect on lamp life due to line voltage fluctuations.

Although one embodiment of the present invention has been shown and described, it is to be understood that still further modifications thereof may be made without departing from the spirit and scope of the appended claims.

I claim:

1. A starting and operating circuit for a discharge lamp comprising a discharge lamp operable at a voltage approaching normal line voltage and provided with filamentary electrodes adapted to be heated to an electron-emitting temperature prior to the initiation of a discharge therebetween, a source of electrical energy of the customary domestic potential for preheating said electrodes and for thereafter sustaining a positive column discharge therebetween, a reactor and a capacitor interposed between said source and one of the electrodes of said lamp to render the operating circuit for said lamp capacitive, an inductance interconnecting the electrodes of said lamp to complete a reactive starting circuit to said source and adapted to initially have a voltage impressed thereacross which is approximately double that of said domestic source but insufficient to initiate a discharge in said lamp, and means in electrical parallel with said inductance and automatically operable to short-circuit the latter and cause the electrodes of said lamp to be heated to optimum electron-emitting temperature from said source and for thereafter removing the short-circuit condition of said inductance with attendant causation of a high voltage surge from said reactor and capacitor sufficiently above the voltage across said inductance to initiate a discharge between said preheated electrodes.

and capacitor sufficiently above the voltage across said inductance to initiate a discharge between said preheated electrodes.

2. A starting and operating circuit for a discharge lamp comprising a discharge lamp operable at a voltage approaching normal line voltage and provided with filamentary electrodes adapted to be heated to an electron-emitting temperature prior to the initiation of a discharge therebetween, a source of electrical energy of the customary domestic potential for preheating said electrodes and for thereafter sustaining a positive column discharge therebetween, a reactor and a capacitor interposed between said source and one of the electrodes of said lamp to render the operating circuit for said lamp capacitive, an inductance interconnecting the electrodes of said lamp to complete a reactive starting circuit to said source and adapted to initially have a voltage developed thereacross which is approximately double that of said domestic source but insufficient to initiate a discharge in said lamp, the constants of said circuit being such that insufficient current initially flows through the electrodes of said lamp to heat the same during the imposition of a voltage higher than line voltage across said inductance, and means in electrical parallel with said inductance and automatically operable to short-circuit the latter and cause the electrodes of said lamp to be heated to optimum electron-emitting temperature from said source and for thereafter removing the short-circuit condition of said inductance with attendant causation of a high voltage surge from said reactor and capacitor sufficiently above the voltage across said inductance to initiate a discharge between said preheated electrodes.

3. A starting and operating circuit for a discharge lamp comprising a discharge lamp operable at a voltage approaching normal line voltage and provided with filamentary electrodes adapted to be heated to an electron-emitting temperature prior to the initiation of a discharge therebetween, a source of electrical energy of the customary domestic potential for preheating said electrodes and for thereafter sustaining a positive column discharge therebetween, a reactor and a capacitor interposed between said source and one of the electrodes of said lamp to render the operating circuit for said lamp capacitive, an inductance interconnecting the electrodes of said lamp to complete a reactive starting circuit to said source and adapted to initially have a voltage impressed thereacross which is approximately double that of said domestic source but insufficient to initiate a discharge in said lamp, and a glow relay tube in electrical parallel relation with said inductance and automatically operable to short-circuit the latter and cause the electrodes of said lamp to be heated to optimum electron-emitting temperature from said source and for thereafter removing the short-circuit condition of said inductance with attendant causation of a high voltage surge from said reactor and capacitor sufficiently above the voltage across said inductance to initiate a discharge between said preheated electrodes.

4. A starting and operating circuit for a discharge lamp comprising a discharge lamp operable at a voltage approaching normal line voltage and provided with filamentary electrodes adapted to be heated to an electron-emitting temperature prior to the initiation of a discharge

therebetween, a source of electrical energy of the customary domestic potential for preheating said electrodes and for thereafter sustaining a positive column discharge therebetween, a reactor and a capacitor interposed between said source and one of the electrodes of said lamp to render the operating circuit for said lamp capacitive, an inductance interconnecting the electrodes of said lamp to complete a reactive starting circuit to said source and adapted to initially have a voltage induced thereacross which is approximately double that of said domestic source but insufficient to initiate a discharge in said lamp, the constants of said circuit being such that insufficient current initially flows through 15

the electrodes of said lamp to heat the same during the imposition of a voltage higher than line voltage across said inductance, and a glow relay tube in electrical parallel with said inductance and automatically operable to short-circuit the latter and cause the electrodes of said lamp to be heated to optimum electron-emitting temperature from said source and for thereafter removing the short-circuit condition of said inductance with attendant causation of a high voltage surge from said reactor and capacitor sufficiently above the voltage across said inductance to initiate a discharge between said preheated electrodes.
